UNITED STATES PATENT OFFICE.

JOHN G. WHILLDIN, OF PHILADELPHIA, PENNSYLVANIA, ASSIGNOR TO THE WHILLDIN POTTERY COMPANY, OF SAME PLACE.

DESIGN FOR A FLOWER-POT.

SPECIFICATION forming part of Design No. 19,339, dated October 1, 1889.

Application filed August 31, 1889. Serial No. 322,621. Term of patent 7 years.

To all whom it may concern:

Be it known that I, JOHN G. WHILLDIN, a citizen of the United States, and a resident of Philadelphia, in the county of Philadelphia and State of Pennsylvania, have invented certain new and useful Designs for Flower-Pots; and I do declare the following to be a full, clear, and exact description of the invention, such as will enable others skilled in the art 10 to which it appertains to make and use the same, reference being had to the accompanying drawings, and to letters or figures of reference marked thereon, which form a part of this specification.

15 Figure 1 of the drawings is a representation of this invention, and is a side view. Fig. 2 is a bottom view.

This invention has relation to designs for flower-pots; and it consists in the novel form 20 and configuration of parts, as hereinafter set forth.

In the accompanying drawings, illustrating this design, the letter A designates the body portion, which is of the form of a conical frus-

tum having its oblique elements slightly convex. Said body portion is surrounded by the marginal offset portion or re-enforcement band B, of cylindrical form, connected to the conical body portion by the annular shoulder C.

30 D is the bottom, which is a plain surface having the rounded studs E projecting downward therefrom at regular intervals, as shown.

What I claim, and desire to secure by Letters Patent, is—

35 The design for flower-pots, consisting of the curved body portion A, surrounded by the cylindrical marginal offset or re-enforcement B and terminating below in a plain bottom surface D, having the downward-projecting 40 studs E, as shown and described.

In testimony whereof I affix my signature in presence of two witnesses.

JOHN G. WHILLDIN.

Witnesses:

PHILIP C. MASI,
MARY BOYKIN.
